UNITED STATES PATENT OFFICE.

WEBB W. AYRES, OF PAVILION, NEW YORK, ASSIGNOR OF THREE-EIGHTHS TO RICHARD WALKER WHITE AND TWO-EIGHTHS TO AMBROSE A. MERRY, BOTH OF ROCHESTER, NEW YORK.

ILLUMINATING APPARATUS FOR PHOTOGRAPHIC COPY BOARDS.

Application filed April 1, 1922. Serial No. 548,595.

To all whom it may concern:

Be it known that I, WEBB W. AYRES, a citizen of the United States of America, residing at Pavilion, in the county of Genesee and State of New York, have invented certain new and useful Improvements in Illuminating Apparatus for Photographic Copy Boards, of which the following is a specification.

10 The object of this invention is to provide an improved illuminating apparatus for illuminating objects on a photographic copy board for the purpose of making a photographic copy thereof.

15 This and other objects of this invention will be fully illustrated in the drawing, described in the specification and pointed out in the claims at the end thereof.

In the accompanying drawing:

20 Figure 1 is a side elevation of the apparatus showing its application to a photographic copying machine, the photographic copying machine being shown in dotted lines in the figure.

25 Figure 2 is a top plan view of the copying board of the machine with the illuminating apparatus attached thereto.

Figure 3 is a vertical sectional view of one of the reflectors used for the illuminating apparatus.

30 Figure 4 is a vertical sectional view of a corner of a copy board with one of the adjustable brackets for supporting one of the reflectors of the apparatus, the reflector shown being a modification of the type illustrated in Figures 1 to 3 inclusive.

Figure 5 is a side elevation of the parts of the apparatus illustrated in section in Figure 4.

40 In the several figures of the drawing, like reference numerals indicate like parts.

My present invention is an improvement over the apparatus illustrated in my prior application No. 343,359 filed December 8, 1919.

45 As illustrated in the drawings the apparatus comprises the reflectors 1, 2, 3 and 4, each of which is mounted on a hollow standard 5. The reflectors illustrated are of the parabolic type and are made

50 preferably of metal with a light diffusing coating provided on the inside thereof which coating has a rough surface. These reflectors have a metal bracket 6 fastened to one side thereof which is made of a

metal band bent to form an angular base 55 to which the standard 5 is attached. For this purpose the upper end of the standard is bent outwardly at an angle thereto parallel to the angular base of the bracket 6. In this way the reflectors are supported at 60 the top of the standards 5 preferably at an angle of about 45 degrees to the copy board 7.

Each of the standards is formed of a tubing which telescopes on a vertical guide 65 8. This guide forms part of an angular bracket 9 of which the horizontal section or guide 10 extends into a support 11 fastened to the under side of each of the corners of the copy board 7. The supports 11 70 are made up of a small vertical rectangular metal frame having a pair of rectangular holes 12 therein, one in each of the vertical sections of the frame 11 and in line with each other. The horizontal guide 10 75 of the angular bracket 9 is rectangular in section and is mounted to slide in the opening 12, 12 in each of the supports 11 so that the reflectors can be moved toward or away from the center of the copy board 7. 80 Mounted in the support 11 between the section 10 of the bracket 9 and the inside of the frame is a leaf spring 13. This spring presses yieldingly against the under side of the section 10 for the purpose of increasing 85 the frictional contact of the bracket 9 with the support 11. The bracket is, therefore, always firmly held in place on the support without impairing the adjustability of the bracket. The spring 13 also prevents chattering when bracket 9 is drawn out. 90

As illustrated in Figure 2, the supports 11 and in turn the reflectors 1 to 4 inclusive are mounted at diagonally opposite points on the copy board 7 at equal distances from the center thereof. The reflectors are pointed to the center of the copy board and are adjustable horizontally as well as vertically so that this holds true no matter how far from the center of the 100 copy board the reflectors have to be grouped in order to properly illuminate the subject to be copied.

The horizontal adjustment of the reflectors is secured by sliding the horizontal 105 guide 10 of the angular bracket 9 in or out of the support 11. The frictional contact which the angular bracket makes with the

support 11 as above pointed out is sufficient to hold the reflectors steady at any distance from the center of the board. Whenever the reflectors are adjusted horizontally on the board a corresponding vertical adjustment must be made. This is secured by raising the hollow standard on the vertical guide 8 of the angular bracket 9 and then fastening it in the desired elevation on the guide by means of the set screw 14 provided near the lower end of each of the hollow standards.

In order to secure the proper vertical adjustment with a corresponding horizontal adjustment each of the horizontal guides 10 and the vertical guides 8 forming the bracket 9 is provided with a series of notches 15 and 16 respectively indicating the corresponding vertical position of the reflector to a given horizontal position thereof. Thus when the horizontal guide 10 is pulled out of the support 11 to the first of the notches 15, the standard 5 must be correspondingly raised on the vertical guide 8 to the first of the notches 16 thereon.

As will be seen from an inspection of the figures, the standards 5 are fastened to the reflectors about midway thereof. To do this the reflectors illustrated in Figures 1 to 3 inclusive are provided with the bracket forming a suitable base to which the standard may be fastened.

In Figures 4 and 5 I have illustrated a cone shaped reflector 17. This reflector has the standards 5 directly fastened to the outside of it about midway thereof to hold the reflector in the proper angular position with regard to the copy board as above pointed out.

Both the parabolic reflectors as well as the conical reflectors when used in connection with this apparatus are provided with a light diffusing and reflecting surface. This is secured by coating the reflecting surface of the reflectors with an aluminum paint or its equivalent giving the reflectors a rough light diffusing surface which breaks up the light rays absorbing some of them so that only certain light rays are reflected onto the copy board. As pointed out in my prior application above referred to, this gives the desired result in that it secures an illumination for the copy board which in efficiency and results excels the mercury vapor lamp heretofore used for this purpose. It will be seen that both the conical and parabolic reflectors are mounted so that they project over the board when in their innermost position. This puts them in better position for copying small papers.

The copy board may be made to rotate on the pivot pin 18 with relation to the position of the reflectors so that the light reflected

from the reflectors can be shifted on the copy board according to the subject to be 85 illuminated thereon.

I claim:

1. In an apparatus for illuminating a photographic copy board, the combination of a series of reflectors grouped at equal distances from the center of the copy board on all sides or corners thereof at a predetermined angle thereto, a support for each of said reflectors mounted on the under side of the copy board, an angle bracket mounted to horizontally slide in and out of each of said supports and projecting above said copy board yielding means adapted to increase the frictional contact of said angle brackets with said supports, each of said angle brackets forming a horizontal and a vertical guide, means for adjustably supporting said reflectors on the vertical guide of said angle brackets and means provided on the horizontal guide and vertical guide of said angle bracket to enable a vertical adjustment of the reflectors to a given horizontal adjustment of said angle brackets.

2. In an illuminating apparatus for photographic copy boards, the combination of a series of reflectors grouped around the copy board at equal distances from the center thereof, a rectangular frame forming a support mounted on the under side of the copy board for each of said reflectors, said frame having a pair of openings provided therein in a horizontal line with each other, an angular bracket mounted to slide in the holes provided in said rectangular frame, a spring interposed between the angular bracket and the rectangular frame to firmly hold said angular bracket in said rectangular frame, adjustable means interposed between said angular brackets and said reflectors to support said reflectors angularly to said copy board, said reflectors being adapted to overhang said copy board or be moved away from it through the adjustment of said angular bracket in said rectangular frame.

3. In an apparatus for illuminating a photographic copy board, the combination of a series of reflectors grouped at equal distances from the center of the copy board, a standard fastened to the outside of each of said reflectors, an angular bracket mounted on the copy board, means adapted to horizontally adjust said angular bracket on the under side of said copy board, said standards being mounted to telescope on said angular bracket to vertically adjust said standards on said angular bracket, means for rotating said copy board with relation to said reflectors.

In testimony whereof I affix my signature.
WEBB W. AYRES.
